WELL PACKER

Clarence M. Jones, Tulsa, Okla., assignor to The
Robinson Packer Company, Tulsa, Okla.

Application August 25, 1939, Serial No. 291,937

3 Claims. (Cl. 166—10)

The invention relates to well packers, and has for its object to provide a step form of packer, formed from a plurality of telescopically engaged members which expand the rubber packer when forced into the rubber packer, and for a substantial distance, thereby insuring a larger area of packing surface between the packer and the well wall. In the step type of packer at present used, where the various steps are rigidly fixed, it has been found that the effective packing area is extremely limited to the upper end of the rubber packer, and the same is true of a continuously tapered mandrel. In the step type, it has been found that the only step that did the maximum expanding was the last one, that is the one of the greatest diameter, and that the effective area thereof was limited to a few inches. In this type of packer a long rubber had to be used in order to have sufficient length for the last step of the mandrel to enter. In the present device by providing a telescopic type of rubber half the usual length can be used and twice as much or more maximum expansion packing area against the well wall can be obtained.

A further object is to provide a telescopic expanding mandrel for a well packer and the sections of the mandrel with means for normally maintaining the mandrel extended and for releasing the mandrel sections from the lower end of the mandrel upwardly when the sections are forced into the packer, thereby allowing the next mandrel section to enter the packer for the step expanding operation.

A further object is to connect the mandrel sections together by means which will shear and allow the sections to progressively enter the packer from the lower end of the mandrel upwardly.

A further object is to provide connecting means between the mandrel sections having upwardly stepped shearing efficiency from the bottom section upwardly and a stop within the packer adjacent the lower end for causing the shearing after each section has entered the packer for substantially its length.

A further object is to provide the mandrel section with limiting means adjacent their ends for limiting the inward and outward movement of the sections.

A further object is to form the mandrel sections from cylindrical members having their lower ends tapered and to proportion the sections whereby said beveled edges or ends will form substantially a conical end adjacent the lower end of the packer for insuring an expansion of the packer at the lower end.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:

Figure 1 is a vertical transverse sectional view 10 through a conventional form of well, showing a tubing string being run in the hole and the telescopic mandrel in extended position.

Figure 2 is a view similar to Figure 1, but showing the lower telescopic section in the packer incident to the weight of the tubing string and when the anchor line engages the bottom of the well.

Figure 3 is a view similar to Figure 1, but showing the second telescopic section of the mandrel within the packer.

Figure 4 is a view similar to Figure 1, but showing all of the telescopic mandrel sections within the packer, and the packer expanded into engagement with the wall for substantially the length of the packer.

Figure 5 is a horizontal sectional view taken on line 5—5 of Figure 1.

Figure 6 is a horizontal sectional view taken on line 6—6 of Figure 1.

Figure 7 is a horizontal sectional view taken on line 7—7 of Figure 1.

Referring to the drawing, the numeral 1 designates a conventional form of well and 2 a tubing string extending downwardly therein. Connecting to the lower end of the tubing string at 3 is the telescopic mandrel, and which mandrel comprises an upper cylindrical section 4 and intermediate cylindrical section 5 and a lower cylindrical section 6.

Connected to the lower mandrel section 6 by means of shearing pins 7 is an anchor pipe 8 which extends downwardly and is adapted to rest on the bottom of the well when the packer reaches a predetermined depth for the expanding operation. The anchor pipe is provided with a conventional form of cage 10 so that gas or fluid can pass upwardly through the anchor pipe and be discharged into the well through apertures 11 above the packer, thereby relieving resistance during the running in operation. The upper end of the intermediate section 5 is connected to the upper section 4 by means of shearing pins 12 and the upper end of the lower section 6 is connected to the lower end of the in-

termidate section by means of shearing pins 13. By referring to Figures 6, 7 and 5 it will be seen that the number of shearing pins increases from the bottom upwardly so that when 5 the tubing string is supported on the bottom of the well the lower mandrel section 6 will shear its connection to the anchor pipe and the lower section will move downwardly into the expansible packer 9 to the position shown in Figure 2 in engagement with the stop flange 14 carried by the anchor pipe; then the intermediate section will shear at 13 and the intermediate section will then enter the expansible packer and move downwardly telescopically on the lower section 10 15 20 25 30 35 40 45 50 until the upper end of the lower section 6 engages the shoulder 15 in the intermediate section, thereby forming a positive downward stop for the intermediate section so the weight of the tubing string will shear the connections 12 between the upper end of the intermediate section and the lower end of the upper section, and then the upper section will move downwardly into the expansible packer and assume the position shown in Figure 4.

It will be noted that the lower ends of the sections 4, 5 and 6 are provided with shoulders 16 which limit the outward movement of the sections in relation to each other when the outer flanges 17 of adjacent sections engage the same, and the inner shoulders 15 and 18 form limiting stops for limiting the inward telescoping of the sections.

The lower ends of the sections 4, 5 and 6 are bevelled as shown at 19 so they will easily enter the upper end of the packer, and when the sections are in telescoped position as shown in Figure 4, a substantially frusto-conically shaped end is formed by registration thereof to force the lower end of the packer body outwardly along with the radial expansion of the packer member on the mandrel section 4. A supporting collar 20 is provided on the anchor pipe 8 beneath the packer for rigidly holding the packer against downward movement.

From the above it will be seen that a packer expanding mandrel is provided for wells, which mandrel is formed from a plurality of telescopically connected members which progressively enter and expand the packer incident to the stepped shearing of the connections between the

sections incident to weight above the packer. It will also be seen that by providing means for expanding the packer for a substantial distance from top downwardly an efficient packer is provided which is not possible in the old type of 5 packer. It has been found that the present device will give a larger wall contact surface with only half the length of packer necessary, for instance eleven inches of rubber packer allows eight and one half inches full vertical wall contact. On the step type, however, a twenty two inch rubber packer, which only binds on its greatest diameter provides only three and one half inches of vertical wall contact, hence it will be seen that applicant's packer is half the length 15 and utilizes substantially all of the packer for packing purposes, thereby increasing the efficiency and at the same time reducing the cost of the packer necessary for a packing operation.

The invention having been set forth what is 20 claimed as new and useful is:

1. A well packing device comprising an expansible packer sleeve, an anchor pipe carried by said sleeve and extending therethrough and adapted to engage the bottom of a well, the lower end of said sleeve being secured to said anchor pipe, an expanding mandrel formed from a plurality of telescopically engaged sleeves, the lower telescopically engaged sleeve being slidably mounted on the anchor pipe, said lower sleeve 30 having an inwardly extending flange in the path of the upper end of the anchor pipe, said annular flange also extending beyond the outer periphery of its sleeve and into the path of an inwardly extending flange carried by the upper end of the next telescopic sleeve above and forming means for limiting the downward movement of the telescopic sleeves on each other and on the anchor pipe.

2. A device as set forth in claim 1 including 40 frangible pins carried by the flanges and extending into the lower ends of adjacent sleeves.

3. A device as set forth in claim 1 including frusto conically shaped lower ends carried by the sleeves and positioned whereby they will form a 45 single frusto conically shaped end for all of the sleeves when in lowered position and the limit flanges of the sleeves are in engagement with each other.
